(57) **CLAIM**

The ornamental design for a wristband rivet, as shown and described.

DESCRIPTION

FIG. 1 is a top perspective view of a first embodiment of a wristband rivet, showing our new design;

FIG. 2 is a right-side elevation view of FIG. 1;
FIG. 3 is a left-side elevation view of FIG. 1;
FIG. 4 is a rear elevation view of FIG. 1;
FIG. 5 is a front elevation view of FIG. 1;
FIG. 6 is a top plan view of FIG. 1;
FIG. 7 is a bottom plan view of FIG. 1;
FIG. 8 is a reduced perspective view of the first embodiment of the wristband rivet, showing our new design in use;
FIG. 9 is a top perspective view of a second embodiment of a wristband rivet, showing our new design;
FIG. 10 is a right-side elevation view of FIG. 9;
FIG. 11 is a left-side elevation view of FIG. 9;
FIG. 12 is a rear elevation view of FIG. 9;
FIG. 13 is a front elevation view of FIG. 9;
FIG. 14 is a top plan view of FIG. 9;
FIG. 15 is a bottom plan view of FIG. 9;
FIG. 16 is a reduced perspective view of the second embodiment of the wristband rivet, showing our new design in use;
FIG. 17 is a top perspective view of a third embodiment of a wristband rivet, showing our new design;
FIG. 18 is a right-side elevation view of FIG. 17;
FIG. 19 is a left-side elevation view of FIG. 17;
FIG. 20 is a rear elevation view of FIG. 17;
FIG. 21 is a front elevation view of FIG. 17;
FIG. 22 is a top plan view of FIG. 17;
FIG. 23 is a bottom plan view of FIG. 17;
FIG. 24 is a reduced perspective view of the third embodiment of the wristband rivet, showing our new design in use;
FIG. 25 is a top perspective view of a fourth embodiment of a wristband rivet, showing our new design;
FIG. 26 is a right-side elevation view of FIG. 25;
FIG. 27 is a left-side elevation view of FIG. 25;
FIG. 28 is a rear elevation view of FIG. 25;
FIG. 29 is a front elevation view of FIG. 25;
FIG. 30 is a top plan view of FIG. 25;
FIG. 31 is a bottom plan view of FIG. 25; and,
FIG. 32 is a reduced perspective view of the fourth embodiment of the wristband rivet, showing our new design in use. The broken lines showing wristbands depicts environmental subject matter that forms no part of the claimed design, while the remaining broken lines shown in the drawings depict portions of the wristband rivet that form no part of the claimed design.

1 Claim, 20 Drawing Sheets
